CURETTE KIT

William F. Rosenberg, Chicago, Ill.

Application January 7, 1948, Serial No. 1,027

4 Claims. (Cl. 206—63.2)

1

My invention relates to first aid and includes among its objects and advantages an instrument and accessories for removing foreign objects from the eye.

In the accompanying drawings,

Figure 1 is a longitudinal section of a kit according to the invention; and

Figure 2 is a perspective of the holder for the curette loop.

In the embodiment of the invention selected for illustration the entire kit is housed in a holder closely similar to the body of a fountain pen. The barrel 10 is of plastic and conventionally threaded at 12 to engage the threads of the cap 14 carrying the conventional clip 16 for carrying the device in a pocket. The curette proper is mounted in the upper end of the barrel and comprises an operative loop 18 of nylon, catgut, horse hair, linen thread, etc. The loop is mounted and held for use in a holder comprising a strip of stainless steel doubled on itself at the bottom at 20 and extending up to form a backing plate 22 and a clamping plate 24. The plate 22 has a turned over lip 26 at its upper end containing a plurality of apertures 28, through any desired two of which the legs of the loop 18 may be threaded. Below the holes 28 the legs are continued down as indicated at 30 toward the bottom of the clamp. It will be apparent that pressing the sides of the clamp together will grip the lower portions of the extensions 30 and this grip, combined with the guidance of the lip 26, will hold the loop proper 18 in any desired condition of adjustment. And this holding is substantially rigid up to the holes 28 leaving the flexibility of the projecting portion dependent on the characteristics of the filament employed.

The plug 32 is a friction fit in the upper end of the barrel 10 and has an axial opening 34 shaped to receive the clamp, with clearance between the clamp and the hole except for the abutments 36 at the top of the plug. Since the opening of the leaves 24 and 22 to receive the extension 30 will cause the clamp to have a tapered formation, thrusting the clamp into the plug will press the leaves together and tighten them to grip the extensions 30, and the subsequent insertion of the plug in the end of the barrel constitutes the loop, plug and barrel a unitary assembly which can conveniently be held in the hand of the user as a tool of suitable size with which to engage a foreign object lodged in the eye or on the eyelid and remove it.

The space below the plug, and the space in the cap 14 above the loop, afford convenient storage

spaces for accessory equipment. I have illustrated a capsule comprising a lower portion 38 and a cap 40 telescoped over the body 38, filled with the medicament 42, which may be ointment or a liquid. Above the capsule I have indicated a small roll of one-quarter-inch gauze 44 and a small supply of aseptic padding 46. Ordinarily, removal of the plug permits easy access to the contents of the barrel by inverting the barrel and jarring it.

10 But the body 38 of the capsule also carries an apertured lug 50 so that a user who prefers may attach a short length of filament 52 to the lug and insert the parts with the filament extending up close to the plug as indicated at 54, so that 15 the contents of the barrel can be lifted out by pulling on the filament. The capsule is of small enough diameter so that the user can conveniently carry some additional pieces of filament wound around the capsule at 54 for replacing the loop 18, 20 either because it has become soiled or because the particular task calls for a softer or a stiffer bit of filament. Additional aseptic padding can be stored at 56 in the top of the cap.

Men who work on railroad trains or in or around railroad yards frequently get particles of soot lodged in the eye. The absence of an aseptic and conveniently available tool for removing such objects not only causes a good deal of lost time, but not infrequently results in infections when a 30 match stem wrapped in a handkerchief that is none too clean, or some other crudely improvised equipment, is used. A kit according to the invention is very convenient to carry and is immediately available for either simple or relatively difficult first aid operations on the eye.

35 Others may readily adapt the invention for use under various conditions of service by employing one or more of the novel features disclosed or equivalents thereof. It will, for instance, be obvious that the clamp might hold a piece of absorbent cotton or of gauze, either in place of or as a supplement to the loop 18. As at present advised with respect to the apparent scope of my invention, I desire to claim the following subject 40 matter:

1. A kit comprising, in combination: a barrel having one end closed and the other open; a detachable cap for the open end of said barrel; a plug in the end of said barrel held in place by friction; a filament holder in said plug; and a filament loop held by and projecting from the upper end of said holder; said holder comprising a piece of sheet metal folded to define clamping arms diverging slightly, with the fold functioning as a hinge; one of said arms projecting be-

yond the other; said projecting arm having a portion bent over across the opening between said arms; said bent-over portion having a plurality of spaced guide holes; said filament having a bight projecting above said holder and legs threaded through selected guide holes; the ends of said legs being clamped between said arms; said plug having an opening shaped to receive said holder; the walls of said opening engaging said arms to crush them together and clamp said filament ends.

2. A filament holder comprising a piece of sheet metal folded to define diverging clamping arms with the fold functioning as a hinge; one of said arms projecting beyond the other; said projecting arm having a portion bent over across the opening between said arms; said bent-over portion having a plurality of spaced guide holes; said filament having a bight projecting above said holder and legs threaded through said guide holes; the ends of said legs being clamped between said arms.

3. A filament holder comprising a piece of sheet metal folded to define diverging clamping arms with the fold functioning as a hinge; one of said arms projecting beyond the other; said projecting arm having a portion bent over across the opening between said arms; said bent-over portion having a plurality of spaced guide holes; said filament having a bight projecting above said holder and legs threaded through said guide holes; the ends of said legs being clamped between said arms; and a support having an open-

ing shaped to receive said holder; the walls of said opening engaging said arms to crush them together and clamp said filament ends.

4. An emergency kit for removing foreign objects from the eye comprising, in combination: a barrel; a removable plug in the end of said barrel; a filament holder on said plug; and a filament loop held by and projecting out of the upper end of said holder; said filament holder being held in operative holding engagement with said filament by wedging it into said plug; said holder being removably inserted in said plug whereby, with said plug remaining undisturbed in said barrel, removal of said holder permits adjustment or replacement of said loop.
